(57) **CLAIM**

The ornamental design of a desk, as shown and described.

DESCRIPTION

FIG. 1 is a top front perspective view of a desk showing my new design.

FIG. 2 is a bottom rear perspective view thereof.

FIG. 3 is a top rear perspective view thereof.

FIG. 4 is a bottom front perspective view thereof.

FIG. 5 is a front view thereof.

FIG. 6 is a rear view thereof.

FIG. 7 is a right side view thereof.

FIG. 8 is a left side view thereof.

FIG. 9 is a top view thereof; and,

FIG. 10 is a bottom view thereof.

The broken line shown in the drawings depict portions of the desk that form no part of the claimed design.

1 Claim, 10 Drawing Sheets
